CLAIM

The ornamental design for a tricycle rear bucket, as shown and described.

DESCRIPTION

FIG. 1 is a perspective unmounted view of a tricycle rear bucket showing our new design, it being understood that the bucket mounts on the rear of a tricycle for play hauling of objects.

FIG. 2 is an unmounted side view thereof, the opposite side view of the tricycle rear bucket being a mirror image thereof.

FIG. 3 is an unmounted rear view of the tricycle rear bucket thereof,

FIG. 4 is an unmounted frontal view of the tricycle rear bucket thereof

FIG. 5 is an unmounted top view of the tricycle rear bucket thereof; and,

FIG. 6 is an unmounted bottom perspective view of the tricycle rear bucket thereof.
